PILLOW BLOCK

Mark E. Andersen, Los Angeles, Calif., assignor to The Fafnir Bearing Company, New Britain, Conn., a corporation of Connecticut

Application June 12, 1951, Serial No. 231,211

2 Claims. (Cl. 308—72)

My invention relates to a pillow block and more particularly to improved pillow block housing means.

It is an object of the invention to provide an improved pillow block which is easy to assemble, simple and inexpensive, quite rigid and effective in use and in general the object is to provide an improved two piece housing in a pillow block.

In the drawings which show, for illustrative purposes only, a preferred form of the invention:

Fig. 1 is a perspective view of an assembled pillow block illustrative of the invention;

Fig. 2 is a central sectional view taken substantially in the plane of the line 2—2 of Fig. 1 but illustrating bolts instead of rivets as securing means.

Fig. 3 is a perspective view of one of the housing plates of the pillow block.

Briefly stated, the invention in its preferred form, includes a pair of housing plates each having an outwardly directed annular housing flange which flanges together form a housing for an antifriction bearing when the plates are secured together face to face. The two housing plates may be secured together by various means such as welding, stitching, riveting as in Fig. 1 and by bolting as in Fig. 2. Each upstanding housing plate has a right-angularly extending base plate formed integrally therewith and extending to both sides of the plane of the housing plate. Each foot or base plate or flange is preferably provided with an opening for a securing bolt and the axis of such hole is preferably in the plane of the upstanding housing plates.

In the specific form illustrated the pillow block includes a pair of upstanding housing plates 5—6 and right angularly extending base plate means 7—8. The base plates are longer than the widths of the upstanding housing plates and the flanges or foot portions 7—8 extend substantially beyond one end of the corresponding housing plates, for example, the end 9 of the flange portion 7 on the housing plate 5 extends transversely of the upstanding plate 5 and to both sides of the plane thereof. The base plate 7, for example, terminates at 10 substantially at the corresponding end or edge of its plate 5 while the other end 9 extends considerably beyond the adjacent edges of the plate 5 and extends as shown transversely at both sides of the upstanding plate 5 and preferably to about the same distance. The upstanding housing plates 5—6 and the corresponding base or foot flanges are preferably duplicates of each other so as to make for interchangeable manufacture and the description given for the plate 5 and its foot flange applies equally to the plate 6 and its flange.

The plates 5—6 are secured together by any known means, for example by means of rivets 11—11 shown in Fig. 1 or bolts 11' as shown in Fig. 2 and the pillow block is preferably held on its support by bolts or other fastening members passing through apertures 12—12 in the respective side portions of the base flanges 7—8. Since each side base flange at one end extends laterally to both sides of each of the upstanding plates 5—6, the holes 12 are preferably placed symmetrically and the axes are preferably located substantially in the plane of the upstanding plates 5—6.

The housing plates 5—6 are arranged for housing a

2

bearing and as illustrated each plate has an outwardly extending annular flange 13 which preferably is of substantially spherical contour at the inside so that the two flanges on the abutting plates 5—6 together form a bearing housing having a generally spherical contour to fit the spherical surface of the outer ring 14 of an antifriction bearing such as the ball bearing shown. The outer bearing ring 14 is preferably of generally spherical form

so as to permit self-alignment and proper fitting within the seat formed by the annular flanges 13—13. The bearing illustrated includes the outer ring 14, a long inner ring 15 and interposed antifriction bearing members such as the balls 16. The bearing may be sealed at each side by means of labyrinth seals 17.

In the form shown the inner ring at one end is provided with an eccentric cam surface 18 to fit a corresponding cam surface on a locking ring 19 whereby upon slight relative rotation between the inner ring 15 and the locking ring 19 both rings will be securely locked to the shaft 20 passing through the inner ring.

The housing parts are formed of pressed steel or the like and are preferably duplicates of each other. The complete pillow block is very light, yet sturdy and serviceable in use. No machining operations on the housing plates are necessary and the necessary holes may be drilled or punched. Thus an inexpensive pillow block has been produced which will provide the advantages of a self-aligning antifriction bearing pillow block at very moderate cost. The means for securing the pillow block to its support may be screws or bolts which pass through the holes 12 in the base flanges. These holes are preferably in the same general plane as the upstanding plates 5—6 so the pillow block will be symmetrically supported and will be well balanced.

While the invention has been described in considerable detail, and a preferred form shown, it is to be understood that various changes may be made within the scope of the invention as defined in the appended claims.

I claim:

1. As an article of manufacture, a plate to form part of a pillow block, said plate comprising a flat generally L-shaped base portion, an upstanding flange integral with the base portion and extending upwardly from the inner side of the leg of the L and terminating short of the base of the L, whereby the base plate at one end extends to both sides of the plane of said upstanding flange, said upstanding flange having an outwardly extending annular flange of generally spherical shape, said base plate having an aperture for a securing means in that portion constituting the base of the L.

2. In a pillow block, a pair of upstanding plates mounted in face to face relation, said plates having complementary outwardly extending annular flanges together forming a generally spherical housing for a bearing, each plate having an integral base flange at substantially right angles thereto, said base flange on each plate extending beyond its respective plate at one edge and extending to both sides of its plate at said edge, said plates being duplicates of each other so that when in face to face relation as aforesaid each base flange at one end will overlap the adjacent flange on the other plate and said base flanges together will form a substantially rectangular base of a width axially of the housing substantially the same as the housing.
